UNITED STATES PATENT OFFICE.

JAMES H. CRAUN AND SCOTT BALDWIN, OF MARION, INDIANA.

AMUSEMENT DEVICE.

1,014,571.

Specification of Letters Patent.

Patented Jan. 9, 1912.

Application filed February 14, 1911. Serial No. 608,538.

To all whom it may concern:

Be it known that we, JAMES H. CRAUN and SCOTT BALDWIN, citizens of the United States, residing at Marion, in the county of Grant, State of Indiana, have invented certain new and useful Improvements in Amusement Devices; and we do hereby declare the following to be a full, clear, and exact description of the invention, such as will enable others skilled in the art to which it appertains to make and use the same.

This invention relates to amusement devices, and particularly those of the aerial type.

15 The object of the invention resides in the provision of a device of the character named which includes a sectional casing in which is adapted to be stored a parachute or other aerial toy, and in providing means whereby 20 the sections of the casing are automatically moved to open position when said casing has reached a predetermined height, so that the parachute or other aerial toy contained therein will be discharged therefrom.

25 A further object of the invention resides in so constructing the device that the release of the sections of the casing will occur when the latter have been automatically positioned so that the free end of the sections 30 thereof will constitute the lowermost portion of the casing, this manner of releasing the sections serving to dispose the interiors of same downwardly and thus more effectively discharge the contents of the casing.

35 With these and other objects in view, the invention consists in the details of construction and arrangement and combination of parts to be hereinafter more fully described and particularly pointed out in the appended 40 claims.

In describing the invention in detail, reference will be had to the accompanying drawing wherein like characters of reference denote corresponding parts in the several 45 views; and in which,

Figure 1 is a view showing the manner of operating the device, the casing which contains the parachute being in mid-air in the position occupied thereby just subsequent to its release to open position, the parachute having been discharged from the projecting casing and the connection controlling the locking device of the casing being in the position it would occupy just 55 previous to returning to the ground under

the influence of gravity; Fig. 2, a plan view of the projecting casing in closed position, with the locking device disposed at the top thereof; Fig. 3, a section on the line 3—3 of Fig. 2; and Fig. 4, a detail perspective view of the projecting casing just released, and showing the parachute lying loosely in one part thereof.

Referring to the drawings, the device is shown as comprising a hollow casing A having substantially the shape of a sphere, and formed of a pair of sections 10 and 11 each of which is hemispherical in shape and which are hingedly connected together at 12 so as to permit said sections to be swung toward and away from each other to open and close the casing. The sections 10 and 11 are normally held in open position by means of a spring 13. This spring has one end fixed to the section 10 and then extended exteriorly of the casing across the hinge 12 and through an opening 14 in the section 11 to the interior of said section. The end of the spring 13 disposed within the section 11 bears against the inner face thereof so that when the sections 10 and 11 are moved toward and away from each other, said spring is energized and constantly tends to force said sections away from each other and thus open the casing. Mounted 80 on the section 10 at the outermost portion of its free edge is a catch pin 15. The inner end of this pin is riveted to the section 10 at 16 and is then carried along the inner face of said section to a point adjacent the free edge of the latter and extended through an opening 17 so as to project outwardly of the casing and form substantially an extension of a diameter of the latter when the same is in closed position. Similarly secured to the section 11 is a catch pin 18 which when the sections 10 and 11 are moved to closed position will extend outwardly from the casing in substantially parallel relation to the catch pin 15.

In order to secure the sections 10 and 11 of the casing against movement to closed position under the influence of the spring 13, a cap 19 formed of cork or other suitable material is passed upon the catch pins 15 and 18 and serves to hold said pins against movement away from each other, which in turn prevents the movement of the sections 10 and 11 to open position under the influence of the spring 13. The catch 19 is se- 110

cured to one end of a connection 20 which is anchored to the ground at 21 and is of a predetermined length.

In using the device, the parachute is stored within the casing A and the sections of the latter are locked in closed position by means of the cap 19. The casing is then projected into the air by hand or otherwise. This being done, it will continue its flight under the influence of its projecting force until it has ascended a distance slightly greater than the length of the connection 20. At this point, the cap 19 being incapable of further upward movement, will be stripped from the catch pins 15 and 18 and thus release the sections of the casing to open position to effect the discharge of the parachute contained within the casing.

It will be noted that as the catch pins 15 and 18 extend outwardly from the casing and that the cap 19 can only be removed therefrom longitudinally of said pins, that before said cap is stripped from the catch pins the latter will be moved so as to constitute the lowermost portion of the casing A before the release of the sections 10 and 11 is accomplished. Now, as these catch pins 15 and 18 are located at the outermost portion of the free edges of the sections 10 and 11, it will be apparent that said sections will always be moved to open position with their interiors disposed toward the ground. The positive positioning of the parts upon the release of the sections of the casing just described will of course render more effective the discharge of the parachute from the casing.

It will thus be seen that there has been produced a device through the instrumentality of which a parachute may be projected to a relatively great height, to cause the parachute to remain in suspension in the air when released for a relatively long period.

What is claimed is:—

45 1. A projecting device comprising a cas-

ing for holding material to be projected and formed of a plurality of hingedly connected sections, means constantly tending to move said sections to open position, a catch pin mounted on each section, a cap 50 covering all of said pins and holding the sections in closed position, a connection of predetermined length having one end secured to the cap and its other end adapted for connection to a fixed part whereby said cap will be disengaged from said pins under the influence of said connection when the casing reaches a predetermined point in its flight and effect the discharge of the contents of the casing. 60

2. A device of the class described comprising a casing formed of a plurality of hingedly connected sections, means constantly tending to move said sections to open position, a catch member on each of 65 said sections, and a locking device engaging said catch members and holding the sections in closed position against the influence of said tendency, said locking device being releasable from said catch members by 70 movement away from the casing in a line extending through said casing.

3. A device of the class described comprising a casing formed of a plurality of hingedly connected sections, means constantly tending to move said sections to open position, a pin on each of said sections extending in a line passing through said casing, and a cap covering all of said pins and holding the sections in closed position 75 against the influence of such tendency, said cap being disengaged from said pins by movement longitudinally of the latter.

In testimony whereof, we affix our signatures in presence of two witnesses.

JAMES H. CRAUN.
SCOTT BALDWIN.
